United States Patent Office.

J. G. EVENDEN, OF CHICAGO, ILLINOIS.

Design No. 5,023, dated June 20, 1871.

DESIGN FOR A WOOD-INCASED CAN.

The Schedule referred to in these Letters Patent and making part of the same.

To all whom it may concern:

Be it known that I, J. G. EVENDEN, of Chicago, in the county of Cook and State of Illinois, have invented and produced a new and original Design for Wood-Incased Cans, of which the following is a specification.

The nature of my design is fully represented in the accompanying drawing, to which reference is made.

The body A of the can is cylindrical, and is incased in wood, w, and preferably surrounded by a hoop, a, at the bottom, and another, a', at the top, said hoops being made either of metal or wood.

The breast or top B of the can is conical, terminating in a short tubular nozzle, n.

Ears e e are attached to the sides, and an air-tube or vent, v, is applied to the breast about half-way between the lower edge thereof and the nozzle.

All the parts are formed and arranged as shown.

Having thus described my invention,

What I claim as new, and desire to secure by Letters Patent, is—

The design for a wood-incased can, herein shown.

J. G. EVENDEN.
